UNITED STATES PATENT OFFICE

MAX SKOLNIK, OF MINNEAPOLIS, MINNESOTA, ASSIGNOR TO INSOLO HOLDING COMPANY, OF MINNEAPOLIS, MINNESOTA, A CORPORATION OF MINNESOTA

PROCESS OF MAKING BUILDING BLOCKS

Application filed November 19, 1928. Serial No. 320,411.

My invention relates to building blocks and the like, and the process of making the same. At the present time, insulation material used in connection with walls of buildings is usually manufactured in sheet form or in the form of flakes. This manner of manufacture not only involves an additional expense for the builder but in cases where the insulation is used as a base for plastering without the addition of metal lath, it has been found to be unsatisfactory. One of the objects of my invention is to provide a building block of insulating material which will be self supporting and at the same time as the wall is constructed will provide a thoroughly insulated wall on both sides. Another object is to provide a block of this character which will effectively serve as a plaster base on the inside and as a base for stucco or similar material on the outside. Another object is to provide a process by which blocks of this character and also similar articles such as roofing tile may be readily manufactured from fibrous material such as straw, the blocks or tiles being subjected to treatment which will make them self-sustaining and fire-resistant.

The full objects and advantages of my invention will appear in connection with the detailed description thereof, and the novel features of my inventive idea will be particularly pointed out in the claims.

In the accompanying drawings, Fig. 1 is a view in vertical section showing a device for treating fibrous material. Fig. 2 is a view in vertical section showing a pressing device. Fig. 3 is an elevational view of a pressing device. Fig. 4 is a sectional view of a drying device. Fig. 5 is a plan view of one form of building block made from my material. Fig. 6 is a view in horizontal section showing how the blocks are arranged to form a wall. Fig. 7 is a view in vertical section on the line 7-7 of Fig. 6. Fig. 8 is an end elevational view of a block. Fig. 9 is a view in vertical section on the line 9-9 of Fig. 10 showing the manner of laying one form of roofing tiles. Fig. 10 is a view taken at right angles to Fig. 9. Fig. 11 is a perspective view of this form of roofing tile. Fig.

12 is a perspective view of another form of roofing tile.

In carrying out my invention, fibrous material such as straw is placed in a receptacle 16 having a charging chute 18 as shown in Fig. 1. A disk 20 is adjustably supported within the receptacle 16 in spaced relation to the bottom thereof by set screws 22 which pass through said bottom and engage in recesses in the lower surface of the disk 20. A disk 24 having corrugations in its lower surface to cooperate with the upper surface of the disk 20 is placed above the latter. The disk 24 is secured to a shaft 26 which passes through a bearing 28 secured to the top of the receptacle 16, the lower end of this shaft being supported in a bearing 30 carried by the disk 20. A solution of an alkali containing from about 75% to 85% of water is introduced into the receptacle 16 in order to make the fibrous material more pliable. Upon rotating the shaft 26 from any suitable source of power, the fibrous material is drawn in between the rotating disk 24 and the stationary disk 20 and is crushed in much the same manner that a match is crushed under foot. The crushing action is preferably continued until the fibrous material is reduced to pieces varying from three-eighths of an inch to an inch in length. When this result has been accomplished, the coarse pulp thus produced is discharged upon opening a door 32 with which the bottom of the receptacle 16 is furnished. This fibrous pulp passes through a chute 34 into a receptacle 36 at the bottom of which there is a pump 38 which when in operation pumps the alkali solution back to the receptacle 16 through a pipe 40. The pump 38 is driven by a belt 42 from a shaft 44 which passes centrally through the receptacle 36 and carries beater arms 46. When the alkali solution has been removed from the receptacle 36, the operation of the pump is stopped. The operation of the beater arms is continued and at the same time a solution of slaked lime reduced to a consistency less than thick paste is introduced into the receptacle 36 upon removing a cover 48 with which the receptacle is provided. The beating operation is continued until the fibers

have been saturated with the lime solution. Before the fibrous mass thus produced is taken from the receptacle 36, the lime solution is withdrawn and held in reserve to be used again. In order to remove the fibrous mass from the receptacle 36, the bottom thereof is provided with a delivery tube 50 containing a normally closed damper 52. Upon opening this damper or valve, the fibrous mass is delivered through the tube 50 into any suitable shaping device. A press for this purpose is shown in Figs. 2 and 3. This press consists of a support 54 which carries a mold box 56 opened at top and bottom and having hinged sides. In order to form a block in the box 56, a lower plunger 58 is moved from the position shown in Fig. 3 up into the position shown in Fig. 2 so that core members 60 carried by the plunger are introduced into the box. The proper amount of fibrous material F is then run into the box through the tube 50. This mass is pressed by means of an upper plunger 62 having a downwardly projecting middle portion 64 which comes down into engagement with the tops of the core members 60 so that a recess is formed in the top of the block as it is pressed into shape. The block is then removed from the press and dried in a suitable drying oven or room. An arrangement for such purpose is shown in Fig. 4 in which a closed chamber having walls 66 is provided. This chamber has a charging door 68 so that the blocks may be placed upon the upper end of an inclined surface 70 extending nearly to the opposite side of the chamber. The blocks gradually slide down the inclined surface 70 and then slide down successive inclined surfaces 72 and 74 to a discharge door 76 located near the bottom of the chamber. Heat is supplied by burners 78 while the moisture passes up a stack 80 provided with a regulating damper 82. The dried blocks are then subjected to a bath of so-called liquid glass or water-glass consisting of silicate of sodium or potassium or both. If the silicate is obtained in commercial form, it should be reduced at least one-third in water. This liquid should be heated and the blocks should also be quite warm when they are immersed. At this time, the lime which is present in the fibrous material unites with the water-glass to form a hard stonelike substance and the material is also rendered fire-resistant. The block is then preferably placed in a second press which is similar to the first one but somewhat smaller and the block is thereby given its final permanent form. Fig. 5 is a top plan view of one form of block which may be produced with the use of my material. As shown this block has vertical side members 84 and 86 connected by cross members 88, 90, 92, 94, 96, and 98, the two end members 88 and 98 being inset from the ends of the block. The cross members 88, 90 and 92 are connected by longitudinal partition members 100 and 102 while the cross members 94, 96, and 98 are connected by longitudinal partition members 104 and 106. The cross members 92 and 94 are not connected by partition members so that a comparatively large vertical opening 108 is left in the central portion of the block for receiving cement when the block is laid. The vertical openings between the side member 84 and longitudinal member 100, the side member 84 and longitudinal 104, the side member 86 and longitudinal member 102, and the side member 86 and longitudinal member 106 are also intended for receiving cement when the blocks are laid as will be understood from Fig. 6 which shows a horizontal section of a block laid in a wall. The side members 84 and 86 and the cross members 88, 90, 92, 94, 96 and 98 are provided with cement anchoring holes 110 in such manner that vertical spaces 112, 114, 116, and 118 have no perforations in their vertical walls. The left hand portion of the block shown in Fig. 6 is taken in horizontal section through the holes 110 while the right hand portion of this figure is in horizontal section above said holes. It will be seen that the inset ends of a block fit half way around studs S of the building, the end of an adjacent block fitting the rest of the way around the stud. As the blocks are being laid in courses, cement is poured so as to fill all of the vertical openings except those designated 112, 114, 116, and 118. In order to prevent these openings from receiving cement, temporary filling blocks B are placed at the tops thereof as shown in Fig. 7 these blocks being removed as the wall is built up so that air spaces are provided in the wall extending from top to bottom. In order to complete the wall and hide the insulating blocks, the two sides of the wall may be plastered or coated with cement or other plastic material as indicated at C and C'. In order to make this coating adhere more firmly, the side members 84 and 86 of the block may be provided with corrugations 120 and 122 as shown in Figs. 7 and 8. It will be understood from Figs. 9, 10, and 11 that my material may be employed for making roofing tile such as the corrugated tile indicated at 124 having a rib 126 at one end and an intermediate rib 128 so that the tile when laid may be made to overlap at the ends as shown in Fig. 10. In order to cause these tiles to overlap at the side edges, each tile is provided with complementary flat side margins 130 and 132 as shown in Fig. 11. In the use of roofing tile, it is important that not only should the material be fire resistant but it should also be thoroughly waterproofed. Therefore, the material after being put through the treatment previously de-

scribed including the silicate treatment and drying is subjected to a spray of bituminous material such as asphalt, rosin or a mixture of the two. When this coating has been applied in heated condition and while it is still hot, crushed marble, granite or similar material is preferably applied and pressed down into the upper surface, thus producing a smooth, finished and attractive appearance.

5 When the tile has thus been treated, the hollows on the underside thereof are preferably filled with loose material indicated at 134, this material being combined with liquid gypsum, and when this is set, a coating 10 of clear gypsum indicated at 136 in plaster-like form is applied which leaves the underside of the tile flat. This serves two purposes. One is that it eliminates sheeting of the roof so that the tile may be laid directly 15 upon strips 138 placed the proper distance apart and supported by customary roof members 140. Fig. 2 shows another form of roofing tile 142 made in the form of a shingle so as to be thicker at the lower end than it 20 is at the upper end and provided with a rib 144 at the lower end and an intermediate rib 146. The rib 146 is located at the beginning 25 of the portion exposed to the weather so that the tiles may be overlapped in the manner 30 of ordinary shingles.

I claim:

1. The process of making building blocks and the like which consists in reducing fibrous material to comparatively small pieces, 35 subjecting the reduced material to the action of a solution of lime, pressing the fibrous mass into shape, drying the pressed material, and treating the dried material with water glass.
- 40 2. The process of making building blocks and the like which consists in subjecting fibrous material to the action of an alkali to make the fibers more pliable, reducing the fibrous material to comparatively small pieces, 45 subjecting the reduced material to the action of a solution of lime, pressing the fibrous mass into shape, drying the pressed material, and treating the dried material with water glass.
- 50 3. The process of making building blocks and the like which consists in subjecting fibrous material to the action of an alkali to make the fibers more pliable, mechanically reducing the fibrous material to comparatively 55 small pieces, subjecting the reduced material to the action of a solution of lime, pressing the fibrous mass into shape, drying the pressed material, treating the dried material with water glass, and again pressing 60 the treated material into shape.
4. The process of making building blocks and the like which consists in reducing fibrous material to comparatively small pieces, subjecting the reduced material to the action 65 of a solution of lime, pressing the fibrous

mass into shape, drying the pressed material, treating the dried material with water glass, and coating the treated material with bituminous material.

5. The process of making building blocks and the like which consists in reducing fibrous material to comparatively small pieces, subjecting the reduced material to the action of a solution of lime, pressing the fibrous mass into shape, drying the pressed material, treating the dried material with water glass, coating the treated material with hot bituminous material, and while the coating is still hot pressing pieces of stonelike material into the surface thereof.

6. The process of making building blocks and the like which consists in subjecting fibrous material to the action of an alkali to make the fibers more pliable, mechanically reducing the fibrous material to comparatively small pieces, subjecting the reduced material to the action of a solution of lime, pressing the fibrous mass into shape, drying the pressed material, treating the dried material with water glass, again pressing the treated material into shape, and coating the treated material with hot bituminous material.

In testimony whereof I hereunto affix my signature.

MAX SKOLNIK.
